UNITED STATES PATENT OFFICE

JOHN B. BLEWETT, OF WELLSVILLE, OHIO, ASSIGNOR TO McLAIN FIRE BRICK COMPANY, OF PITTSBURGH, PENNSYLVANIA, A CORPORATION OF DELAWARE

GRATE STRUCTURE

Application filed May 7, 1927. Serial No. 189,602.

My invention relates to grate structure.

One object of my invention is to provide a furnace that shall have a forced draft at least below the grate.

Another object of my invention is to provide a furnace that shall have a forced draft at least below the grate and in which provision is made for varying the air blast.

Another object of my invention is to provide a grate for a furnace that shall be readily removable from a fire box.

Another object of my invention is to provide a multi-section grate, the different sections of which may be quickly separated.

A further object of my invention is to provide a multi-section grate for a fire box that shall have the section adjacent to the hottest fire bed readily detachable from the main section of the grate.

Another object of my invention is to provide a sloping grate that shall have the lower section readily detachable and replaceable.

In certain types of furnaces it is desirable that air be forced into the fire box above and below the fuel bed. In such furnaces it is preferable that the pressure below the fuel bed shall be materially in excess of that above the fuel bed, and accordingly it is desirable to provide means for regulating such blast, especially when both blasts are attached to the same source of compressed air. Accordingly, I have provided a furnace in which an air conduit is connected to the fire box either below the fire bed only or both above and below the fire bed through adjustable valves. The furnace grate is also perforate in order that air may pass upwardly and circulate through the fuel bed.

I have found that a grate deteriorates more rapidly at its lower section where it is exposed to the hottest fuel than at the upper sections where it is in contact with relatively cold fuel. Accordingly, I have provided a grate that is in two sections, the upper or major section being detachably secured at its upper end to the furnace walls and supported at its lower end by an offset portion having openings therein for the passage of air and

also having provision for the quick attachment of another grate section. In operation I have found that it is rarely necessary to replace the major portion of the grate, but that the lower portion should be replaced from time to time, thereby resulting in a substantial saving in material over the former practice where it has been customary to replace the entire grate structure.

In the accompanying drawings which represent an illustrative embodiment of my invention, but are not a limitation thereof,

Figure 1 is a view, partially in elevation and partially in section, of a kiln embodying my invention;

Figure 2 is an enlarged view of a portion of the invention shown in Figure 1;

Figure 3 is a broken plan view of the furnace grate;

Figure 4 is an end view thereof;

Figure 5 is an end sectional view of a portion of the grate;

Figure 6 is a sectional view of a supporting plate for the grate; and

Figure 7 is a broken side view of a unitary grate structure.

Referring to Figure 1, my invention may comprise a furnace 1, that may be a kiln or connected to a boiler as desired, in which is disposed a fire box 2 and a grate 3 for supporting a fuel bed 4, the flames from which pass upwardly through a chamber 5 into the kiln or boiler chamber 6, and pipes 7 and 8 connected to the fire box, respectively, above and below the grate and supplied with compressed air from a supply line 9. As pointed out hereinafter, however, the pipe 8 may be omitted or cut out of service.

The furnace 1 may be constructed of any desired material. The fire box 2 is provided with a metallic door 11 mounted in the furnace 1 and a supporting and closure plate 12 attached to the door 11 and supported by a beam 13 and a rod 14. Below the plate 12 the chamber 2 is provided with the usual ash pit 15.

Referring particularly to Figures 2 to 5, the grate 3 is constituted by a major section 16 that may be provided with a hook 17 at its upper end for engaging a rod 18 mount.

ed in the door 11 and at its lower end is provided with an offset portion 19 that bears against the plate 12 directly over the beam 13. The outer ends of the offset portion 19 are cut away, as at 21, to provide openings for the passage of air and ashes. A smaller grate section 22 is provided with lugs 23 for insertion into openings 24 in the offset portion 19 of the grate 16 in order that the grate portion 22 may be quickly removed and replaced when desired. The lower end face of the grate 22 is provided with longitudinally extending grooves 25 that provide a passageway for ashes and air when the grate is resting on the plate 12 directly over the supporting rod 14. Both grate sections 16 and 22 are provided with a plurality of upwardly converging openings 26 for the passage of air.

20 The grate 3 and the supporting plate 12 together constitute a partially enclosed chamber that is connected to the pipe 8 and is normally under a greater pressure than is the remainder of the fire box. The plate 12 may be constituted by major and minor sections 27 and 28. The section 28 may be secured to the section 27 by lugs similar to the lugs 23 on the grate section 22, if desired.

25 The pipes 7 and 8 are provided with gates 29 and 31, respectively, for controlling the pressure of the air supplied therethrough.

30 In the operation of the furnace embodying my invention, coal is fed downwardly onto the grate 16 in the usual manner and its temperature increases as it moves downwardly until the area of the greatest heat intensity is found above grate section 22. Air under pressure may be supplied through the pipes 40 7 and 8 from above and below the grate, although it is preferable to have the air pressure confined below the grate considerably in excess of that above the grate, and if desired the connection 7 may be omitted entirely. As the body fuel 4 moves downwardly, some particles of ashes and fuel dust drop through the openings 26 and slide along the plate 12 through the openings 21 and grooves 25 into the ashpit, although the bulk 45 of the ashes are discharged directly from the grate section 22.

50 I have found that after continued use, the grate section 22 may be burned out while the grate section 16 is still in good condition. 55 In such case, I am able to easily remove the lugs 23 from the holes 24 and to bodily remove the grate section 22 and replace it without having to move the entire grate 16. If necessary, the plate section 28 may be removed at the same time.

60 In the event the furnace is operated by supplying air entirely below the grate either by eliminating the connection 7 entirely or by cutting off the flow of air therethrough, 65 the desired relative proportions of air above

and below the grate are obtained by the extent of the fuel bed. By concentrating the fuel bed on the extreme lower portion of the grate and leaving the upper portion substantially clean, considerable air passes above the grate, while by varying the distance the fuel bed is permitted to extend up the grate, the amount available for air passage is correspondingly varied and the desired conditions thereby maintained.

70 Referring to Figure 7, I have shown a unitary grate both ends of which are provided with hooks 32, the extremities of which are provided with grooves 34 corresponding to the grooves 25 in the grate section 22. This form of grate may be secured to the supporting rod 18 at either end since both ends are provided with supporting hooks and grooves.

75 Accordingly, I have provided a fire box in which air under pressure is supplied from above and below the grate in predetermined proportions, and in which the fire moves downwardly across a perforate grate, the lower section of which is readily detachable for renewal when necessary without necessitating the handling of the major section of the grate.

80 As the fuel moves downwardly over the sloping grate at a uniform rate in accordance with the character of the fuel, the depth of the fuel bed and the inclination of the grate, and as the pressure of the air above and below the grate may be controlled at will, it is possible to maintain a controlled air supply to the entire fuel bed during its movement along the grate.

85 While I have shown the fire box as incorporated in a masonry structure, it is to be understood that the fire box may be used in connection with a kiln, boilers, or any other apparatus requiring a fire box of material size.

90 It is to be understood that various changes in the size, shape, disposition and arrangement of the component parts of my invention 95 may be made without departing from the scope of the appended claims.

100 I claim:

1. A grate unit having lugs at one end for attachment to securing means, the other end of the grate being provided with a supporting portion having a bearing surface provided with grooves, whereby, when the grate unit is in engagement with a supporting member passageways are provided for the escape of matter from beneath the grate.

110 2. A grate structure comprising a base having a large portion and a readily removable small end portion, a grate section overlying the large portion of the base and a small grate section removably attached to the large grate section and overlying the small section of the base whereby the smaller sections of the base and grate are removable

without disturbing the larger portion of the base and section of the grate.

3. A grate structure comprising a base having a large portion and a readily removable small end portion, a grate section terminating in a grooved, offset portion resting upon said large base portion with the grooves opening thereto, said grate section having a seat formed at least in part by said offset portion, and an end grate section engaging said seat and having a grooved portion for engaging said end base portion, whereby solid matter moving along the base portions beneath the grate sections escape through said grooves.

4. A grate structure comprising a grate unit provided at one edge with a supporting portion having a grooved bearing surface and forming at least in part a seat, and a 20 second grate unit cooperating with said seat and having a grooved bearing surface at its opposite side, whereby the lower surface of said grate structure is provided with a series of grooves for permitting the escape of solid 25 matter from beneath the grate sections.

5. In a combustion device, a supporting plate therein, a grate section having supporting portions resting on said plate and openings between said portions for discharging 30 air and ashes from the space between said plate and the grate section.

6. A grate structure comprising a bottom plate, a major grate section having supporting feet resting on said plate, and a minor 35 grate section having one end resting on said plate and the other on said major section, removably attached thereto.

In testimony whereof I have hereunto set my hand.
